UNITED STATES PATENT OFFICE.

RICHARD SEED, OF PAWTUCKET, RHODE ISLAND.

GAME.

1,095,934.

Specification of Letters Patent.

Patented May 5, 1914.

Application filed December 18, 1912. Serial No. 737,486.

To all whom it may concern:

Be it known that I, RICHARD SEED, a citizen of the United States, residing at Pawtucket, in the county of Providence and State of Rhode Island, have invented new and useful Improvements in Games, of which the following is a specification.

This invention relates to games.

The principal object of the invention is 10 to provide a simple inexpensive device whereby young and old may obtain a maximum amount of amusement in playing same.

The object of the game which is entitled Cats, is to move disks or similar articles over the board in accordance with the number thrown on the dice and to eventually put these articles which represent cats in the home station. The moves of the cats over the board are retarded by frequently 20 getting on spaces which represent shoes or dogs and the cats are caused to run many hazards in gaining access to the home station.

Other objects of the invention will appear 25 as the following specific description is read in connection with the accompanying drawing which forms a part of this application, and in which:

Figure 1 is a plan view of the board. Fig. 30 2 is a perspective view of the playing disks. Fig. 3 shows a pair of dice.

In the specific embodiment of the invention a board 1 is provided having a plurality of rectangularly arranged squares 2, 35 3 and 4 and a central circular station 5 which is known as the home station and is the goal sought after by each of the players. Each rectangular series or arrangement of squares embodies a plurality of safety 40 squares indicated at A, and a plurality of squares indicated at B which represent a dog. There are also other squares in the series representing a shoe which are indicated by the letter C and another set of 45 squares indicated by the letter D showing spaces which permit the representation of two cats or players' disks. The series of 50 rectangularly arranged squares are connected together by four series of diagonally arranged squares 6, 7, 8 and 9 certain of 55 which have dog spaces B as shown. Arranged outside of each rectangular arrangement of squares are spaces 10 preferably arranged adjoining the shoe squares C for a purpose to be hereinafter described. The safety squares A may be indicated by a

house or other place of safety upon which a cat may climb to get out of reach of the dog while the spaces C may have a representation of an old shoe; the spaces D may 60 preferably have a representation of two cats facing each other with arched backs and their mouths open screeching at each other. These pictures add to the ornamental feature of the board and provide means for 65 notifying the player that his cat has been struck by an old shoe or chased by a dog.

The game may be played by either one or more players up to four, each player having two disks or cats which are adapted to be 70 moved around in accordance with the number thrown on a pair of dice which are used in playing the game. A player must throw a "5" upon the dice before he can begin. This entitles him to throw again and 75 should he throw a 2 the move would put him on space B in traveling around the rectangular arrangement of squares 2, each player starting at one of the corner safety squares A. In this instance the cat would 80 be chased back to the nearest place of safety which would be the initial starting point. The next player would then throw the dice and move in accordance therewith. If the player moved 3 points on to a blank space 85 such as is shown at E the cat would remain in this position until the player's next turn. If upon a second throw he threw 2 on the dice the cat would be moved off into the adjoining space 10 being considered to be hit 90 with a shoe as will be readily appreciated. The spaces 10 may be considered resting or recuperating stations or the cat or disk may be considered then out of the play or any other suitable arrangement may be made in 95 the rules by which the game is played. To play the game properly, it is necessary for each cat to travel the complete round of the outer arrangement of squares and then across the diagonal series of squares adjoining the starting point and the next inner series of squares 3; after traveling around this arrangement of squares the cats are moved inwardly to the inner series of squares 4, and after passing around this 100 into the home station 5. The first player getting his cats into the home station is considered to have won the game. The squares and the pictures are printed upon a board in any suitable manner in actual practice, 110 but may be raised therefrom if desired, or the whole sheet may be printed in one color.

and pasted upon a board so as to make the construction cheap and within the reach of all.

What is claimed is:—

- 5 1. Game apparatus comprising a board having a plurality of series of rectangularly arranged squares, a plurality of series of squares connecting the rectangularly arranged series, rest stations adjoining certain of the rectangularly arranged squares, playing devices movable over the board, and chance devices for determining the movement of the playing devices.
- 10 2. Game apparatus comprising a board having a plurality of rectangularly arranged series of squares thereon, said squares being arranged in parallel relation one to

the other and one within the other, certain of said squares representing hazards, a plurality of rest station squares offset with relation to the rectangularly arranged squares and opposite certain of the hazards, a plurality of diagonally arranged squares connecting the rectangularly arranged squares and having hazards thereon, playing disks 25 adapted to be moved over the board and chance devices for determining the movement of said playing devices.

In testimony whereof I affix my signature in presence of two witnesses.

RICHARD SEED.
